FLUSH-TANK-OPERATING DEVICE.

13,391.

Specification of Reissued Letters Patent. Reissued Mar. 26, 1912.

Original No. 821,002, dated May 22, 1906, Serial No. 268,641. Original Reissue No. 12,910, dated January 12, 1908, Serial No. 458,144. Application for this reissue filed January 24, 1910. Serial No. 539,913.

To all whom it may concern:

Be it known that I, BERT O. TILDEN, a citizen of the United States, residing in New York, in the county of New York and State 5 of New York, have invented certain new and useful Improvements in Flush-Tank-Operating Devices, of which the following is a specification.

The invention has reference to apparatus 10 for operating the flush-tanks which are connected to latrine-bowls, and is more especially directed to such tanks as are arranged contiguous to the bowl. In this class of apparatus it is highly desirable that the mechanism be very easily operable, and such also, 15 as will possess extreme simplicity as to number and action of parts.

The object of the invention is to provide 20 mechanism in which the flush-valve is adapted for operation by a handle freely movable in opposite directions so that there will be no difficulty in operating the same, even though a person is previously ignorant of how to do so, and which is peculiarly connected to the flush valve so as to actuate the latter by the application of the slightest 25 pressure. The improved mechanism is therefore extremely sensitive as to action of parts and, having in mind the special purpose 30 of the invention, this is highly advantageous.

Specifically speaking the invention consists of an operating device for actuating the flush valve lever for unseating the flush 35 valve that may be rocked in either direction to tilt the lever to open the valve, and which will restore itself unassisted to normal position ready for a subsequent operation, the said device being arranged adjacent the 40 user of the closet.

An embodiment of the invention is illustrated on the accompanying sheets of drawings, whereon—

Figure 1 illustrates a perspective view of 45 a latrine-bowl and a flush-tank with the invention applied thereto. Fig. 2 illustrates a front elevational view in section of said tank. Fig. 3 illustrates an end elevational view in section of the same. Fig. 4 illustrates a top plan view of said tank, and Figs. 5 and 6 illustrate diagrammatic views showing the operation of a portion of the operating mechanism.

In the several illustrations similar characters of reference apply to similar parts. 55

The invention appertains more particularly to that class of flush-tanks which is here designated in a general way as 7 and which is arranged contiguous to and connected by suitable connections 8 above latrine-bowl 9, the tank being supplied in the present instance by a pipe 10, emanating from the floor 11, and which connects with the tank 7 from the bottom by a union 12. Within the tank 7 is located the usual supply-valve 13, carried by a seat 14, and which is operated by a lever 15, fulcrumed at 16, and which is connected by a link 17 to a lever 18, fulcrumed at 19, and which is operated by a float 20, secured thereto by a 70 rod 21, it being understood that when the float is precipitated by gravity the valve 13 will leave its seat 14 to admit the water into the tank and the water will raise the float to close the valve. Also within the tank is the 75 usual valve, comprising a seat 22 and plunger 23, which normally rests upon the seat and which plunger is actuated by a lever 24, fulcrumed to the wall of the tank at 25 and connected to the plunger by rods 80 26 and 27, the latter in the present instance being guided by a brace 28, suitably disposed within the casing, and which may surround or be connected to the overflow 29.

The lever 24 is provided on its upper side 85 with bearing portions, which may be of any suitable character and formed and located in any suitable manner at that side of the fulcrum 25 which is opposite to that where the rod 26 is connected to the lever. In the 90 present instance these upper portions are in the form of depressions 260 and 270 upon the upper side or edge of the lever 24, and upon these surfaces are adapted to ride the extremities 280 and 290 of a rocking lever 95 30, fulcrumed at 31 intermediate of the depressed portions 260 and 270 and somewhat above the lever 24 when it is the same as in its normal position, and in order that the lever 24 may clear the fulcrum 31 said lever 100 may, if desired, be depressed or bent, as at 32. The depression 32 permits the location of the contact points 280 and 290 of the rocking lever 30, and the fulcrum 31, in the same plane, or at right angles to the handle 34. 105 The fulcrum 31 in the present instance com-

prises a spindle, which in the present instance carries a squared extremity 33, which extends to the outside of the wall of the tank 7 and carries a handle 34, which may be 5 rocked, so that the lever may be operated to lift the plunger 23 from its seat 22. If the handle 34 is turned to the left and as seen in Fig. 5, the extremity 280 of the rocking lever 30 will bear upon its corresponding bearing 260 and lift that end of the lever 24 which is connected with the rod 26. If the handle should be turned to the right, as seen in Fig. 6, the free end 290 of the rocking lever 30 will take in its corresponding bearing 270 and lift the lever 24 in a similar manner as above explained. Thus it will be seen that this handle may be turned in either direction, right or left, and the action of the lever 24 will be the same to lift the 10 plunger 23. The form of the ends of the lever 30 is such that the contact extremities thereof, which coöperate with the flush-valve lever 24, are spaced from each other as well as from the fulcrum 31, and further 15 more, the handle 34 is pendent from the fulcrum. This construction affords a maximum amount of leverage in operating the handle, accomplished by a comparatively small degree of movement thereof, and with 20 a minimum amount of friction between the parts 30 and 24. The extremities 280 and 290 afford practically point contacts which effect very quick action of the lever 24 in response to pressure on the handle 34. The 25 sensitiveness of operation of the flush-valve 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

which form the connection between the lever 24 and valve 23. This feature consists of bending the lower end of rod 26 laterally as illustrated to provide an arm 26', which is looped or perforated to receive the upper 70 end of rod 27, and to allow either of said rods to move freely toward or away from the other during the interval in which the valve 23 is held away from seat 22 by its own buoyancy. Thus when the handle 24 75 is rocked in either direction, as shown in Figs. 5 and 6, the long arm of lever 24 is tilted upwardly, lifting rod 26, which in turn lifts rod 27, and the latter raises the valve after which the flushing begins. The 80 operation of all the parts named is effected practically instantaneously by the relatively short movement of the handle 34. As it requires some time for the water to discharge through the comparatively small flush pipe 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

The arm of the lever 30, remote from the fulcrum 25 of the lever 24, is made longer than the opposite or adjacent arm. When the handle 34 is moved to the right, therefore, the force required to actuate the lever 24 by engagement of the short arm of lever 30 therewith, is substantially equal to that required to accomplish the same result if the handle is moved in the opposite direction and the longer arm of the lever 30 engaged with the lever 24. Or in other words, the flush valve will be raised to the required height by the same angular swing of the handle, regardless of the direction of such swing.

The practical advantages of the above are evident.

Having thus described this invention, I claim—

- 20 1. In combination with a closet low-down flush-tank, of a flush-valve within said tank, a rocking lever pivoted within the tank and connected at one side of its fulcrum with the valve and having at the other side of its fulcrum a pair of bearing-faces spaced apart, a spindle projecting through the wall of the tank and provided on its outer end with a fixed operating-handle located within reach of the user seated on said closet, and having fixed on its inner end a rocking lever, likewise having a pair of bearing-faces spaced apart and coöperating with the bearing-faces of the valve-lever, so that on the swinging of said operating-handle in either direction 35 from its normal position the free end of the valve-lever will be depressed and the valve operated.
2. In combination with a closet low-down flush-tank and with a flushing-valve within said tank, of valve-operating mechanism comprising two members, one a relatively long valve-operating lever pivoted within the tank and connected at one side of its fulcrum with the valve and having at the other side of its fulcrum a bearing-face, and a relatively short arm located at one side of the fulcrum of said valve-lever and having a bearing-face in position to engage the bearing-face of the valve-lever, and all located 45 within the tank, a spindle projecting through the wall of the tank with its inner end connected to said arm and forming the fulcrum thereof, and an operating-handle rigidly secured to the spindle on the outside of the tank and within reach of the user seated on said closet so that on the swinging of said handle from its normal position the free end of the valve-lever will be depressed by the arm and the valve operated.
- 50 3. In combination, a flush tank, a flush-valve within said tank, a flush-valve lever

pivoted between its ends and connected at one end with the flush-valve, a spindle mounted on said tank, a rocking lever carried by the spindle and having a contact extremity arranged to engage the opposite end of the valve lever, and a pendant gravitational handle located at right angle to said contact extremity and fixed on the spindle for actuating the valve lever, said handle being 65 adapted to gravitate to its normal pendent position after movement thereof so as to instantly relieve the flush-valve lever of pressure after raising the flush-valve.

4. In combination, a flush-tank, a flush-valve mounted therein, a flush-valve lever pivoted between its ends to a side of the tank and connected at one end with the flush-valve, a spindle mounted so as to extend through a side of the tank, a rocking 75 lever secured between its ends to one end of the spindle, the opposite ends of said lever being spaced from the spindle and constituting contact extremities adapted to engage the end of the flush-valve lever opposite that 80 connected with the flush-valve and at spaced bearing points, said flush-valve lever being formed with a depression receiving the spindle aforesaid, whereby the contact extremities of the rocking lever are in the same 85 plane as the spindle, and a pendent handle fixed on the other and outer end of the spindle for rocking the lever carried thereby, said handle being arranged at a right angle to the contact extremities aforesaid and 90 adapted to gravitate to its normal pendent position after actuation hereof and in order to instantly relieve the flush-valve lever of pressure thereon when the flush-valve has 95 been raised.

5. In combination, a flush tank, a flush valve therein, a flush-valve lever pivoted between its ends and connected at one end to the flush valve, a rocking lever pivoted between its ends to provide end arms of unequal 100 length, the extremities of the rocking lever being arranged to engage the end of the flush-valve lever opposite that connected to the valve, and an operating handle for the rocking lever, the longer arm of the rocking 105 lever being the more remote from the fulcrum of the flush-valve lever, whereby the operating handle is movable in either of opposite directions by substantially the same amount of force.

This specification signed and witnessed this 20th day of January 1910.

BERT O. TILDEN.
